DESIGN FOR A COMBINED STIRRUP AND TOE GUARD

Aubrey F. Hart, New York, N. Y.

Application June 23, 1937, Serial No. 70,024

Term of patent 14 years

To all whom it may concern:

Be it known that I, Aubrey F. Hart, a citizen of the United States, residing at New York, in the county of New York and State of New York, have invented a new, original, and ornamental Design for a Combined Stirrup and Toe Guard, of which the following is a specification, reference being had to the accompanying drawing, forming a part thereof.

I claim:

The ornamental design for a combined stirrup and toe guard, as shown.

AUBREY F. HART.
